UNITED STATES PATENT OFFICE.

HARRY RANDOLPH VAN DEVENTER, OF SUMTER, SOUTH CAROLINA, ASSIGNOR TO
SPLITDORF ELECTICAL COMPANY, OF NEWARK, NEW JERSEY, A CORPORATION
OF NEW JERSEY.

IGNITION DEVICE.

1,255,069.

Specification of Letters Patent. Patented Jan. 29, 1918.

Application filed September 18, 1917. Serial No. 191,983.

To all whom it may concern:

Be it known that I, HARRY R. VAN DEVENTER, a citizen of the United States, residing at Sumter, in the county of Sumter 5 and State of South Carolina, have invented certain new and useful Improvements in Ignition Devices, of which the following is a specification, reference being had to the accompanying drawing.

10 The invention relates to an ignition device for internal combustion engines, and more particularly to an ignition device including electrodes, a magneto generator electrically connected thereto, and a tripped 15 spring actuated mechanism for operating said generator.

An object of the invention is to provide an ignition device of the above character with a two part supporting bracket, the 20 generator being mounted on one of the said parts and the electrodes being mounted on the other part.

A further object of the invention is to provide a two part supporting bracket of 25 the above character, wherein the trip lever for actuating the springs which operates the generator is mounted on the part of the supporting bracket carrying the electrodes.

A still further object of the invention is 30 to provide a two part supporting bracket of the above character with means for independently attaching and supporting the bracket parts.

Another object of the invention is to provide 35 a two-part supporting bracket, wherein the adjacent faces are formed with interlocking connections so that the parts of the bracket are held in a predetermined relation to each other.

40 These and other objects will in part be obvious and will in part be hereinafter more fully disclosed.

In the drawings, which show by way of 45 illustration one embodiment of my invention;

Figure 1 is a side view of a supporting bracket embodying my invention with the parts of the ignition device assembled thereon;

50 Fig. 2 is a front view of the same, with the magneto removed; and

Fig. 3 is a plan view of the supporting bracket with the magneto, the electrodes and the actuating mechanism removed therefrom.

My invention consists broadly in an ignition device which includes a two-part supporting bracket. One of the parts of the bracket carries the ignition electrodes, while the other part of the bracket carries the magneto generator. The generator is electrically connected to the electrodes. One of the electrodes is preferably movable for a make-and-break ignition. The movable electrode and the flux shifting member of the generator are operated by a tripped spring actuating mechanism, and the trip lever of the spring actuating mechanism is mounted on the part of the bracket carrying the movable electrode. This trip lever is operated by the well known push-rod carrying a trip finger. The thrust of the push-rod against the tripper lever is borne by the part of the bracket supporting the electrodes and therefore there is no tendency on the part of the push-rod, when actuating the tripping lever, to wear loose the section of the bracket carrying the generator. The two parts of the bracket in the present embodiment of the invention are independently mounted.

Referring more in detail to the drawings, my invention consists of an ignition device including a two part supporting bracket S. This supporting bracket as more fully shown in Fig. 2, consists of two parts, one of which is indicated at 1, and the other is indicated at 2. The part 2 of the supporting bracket is provided with a sleeve 3, which projects through the cylinder wall. The cylinder wall is indicated at C, in Fig. 1 of the drawings. The projecting sleeve 3, is preferably formed integrally with the part 2 of the supporting bracket. Mounted in this sleeve is a fixed electrode 4, and a movable electrode 5. These electrodes are provided with ignition points 6 and 7, respectively. The electrode 4 is properly insulated from the sleeve 3. The movable electrode at its outer end carries an arm 8. A spring 9, bearing at one end against the arm 8 and at its other end against an abutment 10, on the bracket 2, normally holds the ignition points in contact.

The part 2 of the bracket lies against the outer surface of the cylinder wall and is clamped in place by a stud bolt 11, on which a nut 12, is threaded.

The section of the bracket 1, is also pressed against the outer surface of the

cylinder wall and is secured in place by two stud bolts 13 and 14. The upper end of the bracket part 1, is slotted at 15, to receive the upper stud bolt, while the lower part 5 of the bracket is perforated to receive the stud bolt 14. Suitable nuts 16, are threaded onto these bolts 13 and 14 to clamp the bracket in place. The lower end of the bracket part 1, projects out from cylinder 10 and is formed with a horizontal shelf 17. The generator which is indicated at G, is mounted on the shelf and is held thereon by bolts 18, which extend up through openings in the shelf and are threaded into the 15 base of the generator.

As will be apparent from Fig. 2, of the drawings, the supporting bracket is directed vertically to form the parts 1, and 2, and the adjacent faces are milled so as to form 20 smooth contact faces. One of these faces is formed with recesses 19, while the other bracket part is formed with corresponding shaped projections 20, which fit into the recesses and hold the two parts of the bracket 25 in a predetermined relation to each other.

The generator and the movable electrode are operated by a spring actuated tripped mechanism consisting of a trip lever 21, mounted on a suitable supporting shaft 22, 30 which is fixed to the part 2, of the supporting bracket. This tripping lever is provided with pins 23 and 24. An actuating spring 25 engages a roller 26, on the pin 23, and also engages a roller 30, on a pin 31, 35 carried by the upper end of the bracket part 2. An actuating spring 32 engages a roller 33, on the pin 24 and also a roller 34 carried by the projecting lug 35, mounted on the bracket part 11, adjacent the shelf 17, 40 which supports the generator. These actuating springs normally move into alignment. The tripping lever is formed with a shoulder 36, which is adapted to be engaged by a trip finger 37, carried by the push-rod which 45 is operated by the engine. As the trip finger moves to the left as viewed in Fig. 2, it will move the trip lever in a clockwise direction until a certain position or point is reached when the trip finger slips from the 50 shoulder and allows the springs to return said trip lever to normal position. The trip lever is provided with a cam shoulder 38, which strikes the arm, 8, on the movable electrode, causing the electrodes to separate 55 and produce a spark. The generator is provided with a forked arm 40, which engages the pin of the trip lever so that this movement of the trip lever through the action of the springs also quickly shifts the flux shifting member of the generator. This produces the current for ignition.

From above it will be apparent that the thrust of the push finger on the tripping lever and the jar incident to the actuation 65 of the springs is borne by part 2 of the sup-

porting bracket; and therefore there is no tendency to loosen the supporting bolts carrying the parts 2 of the bracket which supports the generator. Furthermore, the part of the supporting bracket which projects 70 out from the cylinder and carrying the generator is more liable to be broken than the other part of said bracket. If the shelf carrying the generator is broken, it is only necessary to remove and replace part 1, of the 75 supporting bracket. Then again, as all the strain is carried by part 2 of the supporting bracket, it may be made of cast metal of heavy construction, while part of the supporting bracket may be made of stamped metal, and thus the cost of manufacturing 80 the supporting bracket greatly reduced.

It is obvious that minor changes in the details of construction and the arrangement of the parts may be made without departing 85 from the spirit of the invention as set forth in the appended claims.

Having thus described my invention, what I claim as new, and desire to secure by Letters Patent, is:—

1. An ignition device comprising a two part supporting bracket, means for independently supporting the parts of the bracket, ignition electrodes carried by one part of said bracket and a generator carried by the other part of said bracket and electrically connected to said electrodes. 90

2. An ignition device comprising a two-part supporting bracket, means for independently supporting the parts of the 100 bracket on the cylinder wall of the engine, ignition electrodes carried by one part of said bracket and a generator carried by the other part of said bracket and electrically connected to said electrodes.

3. An ignition device comprising a two part bracket, means for independently supporting the parts of the bracket on the cylinder wall of the engine, a fixed and a movable electrode carried by one part of said 110 bracket, and a generator carried by the other part of said bracket and electrically connected to said electrodes. 105

4. An ignition device comprising a two-part supporting bracket, means for independently supporting the parts of the bracket on the cylinder wall of the engine, ignition electrodes carried by one part of said bracket and a generator carried by the other part of said bracket and electrically 115 connected to said electrodes, and an interlocking connection between the bracket parts whereby the same may be held in a predetermined relation to each other.

5. An ignition device comprising a two-part bracket, means for independently supporting the parts of the bracket on the cylinder wall of the engine, a fixed and a movable electrode carried by one part of said 125 bracket, and a generator carried by the 130

other part of said bracket and electrically connected to said electrodes, and an interlocking connection between the bracket parts whereby the same may be held in a predetermined relation to each other.

6. An ignition device comprising a two-part bracket, means for independently supporting the parts of the bracket on the cylinder wall of the engine, a fixed and a movable electrode carried by one part of said bracket, and a generator carried by the other part of said bracket and electrically connected to said electrodes, and a trip lever carried by said bracket part supporting the electrodes for operating the movable electrode and for actuating the generator.

7. An ignition device comprising a supporting bracket, said bracket being divided vertically, electrodes carried by one part of said bracket and a generator carried by the other part of said bracket and electrically connected to said electrodes.

8. An ignition device comprising a supporting bracket, said bracket being divided vertically, electrodes carried by one part of said bracket and a generator carried by the other part of said bracket and electrically connected to said electrodes, and means for

independently supporting the parts of said bracket.

9. An ignition device comprising a supporting bracket, said bracket being divided vertically, electrodes carried by one part of said bracket and a generator carried by the other part of said bracket and electrically connected to said electrodes, the adjacent faces of the parts of the bracket having interlocking members for holding the same in a predetermined relation to each other.

10. An ignition device comprising a supporting bracket, said bracket being divided vertically, electrodes carried by one part of said bracket and a generator carried by the other part of said bracket and electrically connected to said electrodes, and means for independently supporting the parts of said bracket, the adjacent faces of the parts of the bracket having interengaging lugs and recesses for determining the vertical positions of the parts relative to each other.

In testimony whereof I hereunto affix my signature in the presence of a witness.

HARRY RANDOLPH VAN DEVENTER.
